[57] CLAIM

The ornamental design for a hand-held body massager, as shown and described.

DESCRIPTION

FIG. 1 is a perspective view of a hand-held massager showing my new design;

FIG. 2 is a left side view thereof; the right side view is a mirror image thereof;

FIG. 3 is a bottom plan view thereof;

FIG. 4 is an end view thereof; the other end view is a mirror image thereof; and

FIG. 5 is a top view thereof.
